UNITED STATES PATENT OFFICE.

HENRY E. TOLMAN, OF SHELBOURNE, MASSACHUSETTS.

ROOFING OR STAGING BRACKET.

DESCRIPTION forming part of Letters Patent No. 351,008, dated October 19, 1886.

Application filed September 2, 1886. Serial No. 212,742. (No model.)

To all whom it may concern:

Be it known that I, HENRY E. TOLMAN, of Shelburne, in the county of Franklin and State of Massachusetts, have invented a new and 5 useful Improvement in Roofing or Staging Brackets, of which the following is a specification.

The object of my invention is to properly and conveniently form or arrange a bracket for the 10 purpose of supporting boards, shelving, or platforms upon a slanting roof, thus constituting a staging for the purpose of assisting workmen engaged in building or repairing the same.

Another object of my invention is to conveniently arrange or form an article, so that any 15 one desiring to ascend a slanting roof can so do without other assistance of any kind, after reaching the eaves of the building.

In order to fully explain my invention, I will 20 refer to the drawings, in which Figure I shows a perspective view of my invention ready for use. As will be seen, my invention is composed and manufactured of two separate pieces of metal, (steel preferred,) A showing the outside frame, which is formed or bent at angles, 25 for the purposes hereinafter described.

K K show the portion of my bracket upon which the boards or staging rests, said brackets being placed upon the roof from five to six 30 feet apart, and used in the same manner in which old-fashioned braces would be.

B shows the projection, which is forced or shoved underneath the shingle as far as the shoulder C.

35 C shows a shoulder, which is formed by bending the frame, and arranged for the purpose of supporting my bracket and keeping the same in its proper place, said shoulder resting against the base of the shingle under which 40 the projection B is placed.

D D show two spurs, which are most conveniently formed by cutting or gouging out a portion of the base or lower end of the outside frame, said spurs engaging with and resting 45 upon the roof or shingles for the purpose of sustaining my bracket in its proper place.

E shows a small spur or projection, which is formed upon that part of the frame on which the board rests for the purpose of preventing 50 said board from slipping or moving from the bracket.

F shows the inside frame, which is bent in

an oval form and riveted or fastened to the outside frame at the point L.

G shows the projection or end of the inner 55 frame, which is pushed or forced under the shingles at the same time and in the same manner as the projection B, heretofore described.

H H show spurs formed at the other end of the inner frame in the same manner as the 60 spurs D D, and used for the purpose of helping and assisting the spurs D D to more securely and safely support the bracket in its position.

I would now state that the projection B and 65 the end of the inner frame, G, are sharpened for the purpose of being more easily inserted underneath the shingles.

When a person desires to use my invention, the bracket is grasped at the part L, holding 70 the bracket so that the projection B is pointed towards the ridge-pole of the roof. The projections B and G are then forced or pushed under the shingles until the shoulder C rests against the base of the shingle under which 75 the projection B is placed. This brings the spurs H H and D D so that the same rest upon the roof, and thus after two or more are placed in their proper position my brackets are ready to support the boards or staging, as shown by 80 Fig. II, which is another perspective view of my invention attached to a roof, and in which figure corresponding letters represent corresponding parts, the same as shown in Fig. I, P P in said Fig. II showing the roof. 85

It is perfectly apparent from the above description that it is utterly impossible for my bracket to move or be displaced from its proper position when in use.

The principal difference between my invention and those heretofore in use is as follows: 90 All other brackets that in the least resemble mine have consisted of a single piece of metal, or perhaps a somewhat similar character or design as my outside frame, which, used alone, is 95 very imperfect and unsafe for the following reasons: In the first place, there are only one set of spurs resting one on shingle only, thus making that bracket unsafe for such use. Another great objection would be in the fact 100 that there is nothing to prevent the base or lower part of the frame from lifting up, while in my invention I conquer these two great difficulties by providing this inside frame, which

gives an additional set of spurs resting on the roof in two different places, and an additional projection, which keeps the lower part of the frame firmly down against the roof, thus making my bracket doubly secure, and, as I claim, perfectly safe.

I would further state that my bracket can also be used as a support for staging on the side of a house by simply lengthening or extending the ends D D, so that those spurs would meet a perpendicular object, and then force the projections B and G underneath the clapboards in the same manner as underneath the shingles.

15 In regard to the second object of my invention heretofore mentioned, I would state that a person desiring to use my invention for that purpose takes the requisite number of brackets with him to the eaves of the house, and affixing one to the roof, as instructed, steps on that as a support, and affixing another, continues to employ that method until he arrives at the desired place. This is especially applicable in cases of fire.

20 25 I would further state that the inside frame is connected with the outside frame at L, and

not at the point R, as perhaps would be supposed necessary. The reason for that is as follows: By leaving the frames at R disconnected I am able to provide against the extreme variation in the thickness of shingles, for being disconnected at said point R allows the spurs H to adapt themselves to the usual variation in thickness of shingles and still not weaken the invention in the least.

30 I would finally state these brackets can be manufactured in a double or treble form as well as singly, when so desired.

What I claim as my invention is—

An article of the form described, consisting 40 of the outside frame, A, having the projection B and the shoulder C, also the spurs D D, and the spur E, connected with the inside frame, F, having the spurs H H, and the projection G, all combined and operating together, substantially as described, and for the purpose specified.

35 HENRY E. TOLMAN.
